LATCH FOR HEDDLE FRAMES

John Walker, Jr., Melrose Park, Pa., assignor to
 Walker Manufacturing Company, Inc., Philadelphia, Pa., a corporation of Pennsylvania

Application December 28, 1934, Serial No. 759,439

4 Claims. (Cl. 139—92)

The object of the invention is to provide improvements in latches for heddle frames, and particularly in latches which are designed to operatively support single heddle bars, both in relation with the frame itself and with respect to each other, as compared with latches which are designed to operatively support a plurality of such bars in parallel relation with one another.

In heddle frames which are generally of considerable length, it is necessary to support the usual heddle bars at one or more points intermediate of their ends, in relatively fixed relation with respect to the rails of the said frames, yet the support must be of such character as to permit the heddles carried by said bar to be readily shifted past the positions of such supporting means, whenever and in such number as may be desired.

In the usual latch or hook by which single heddle bars are operatively supported, there is inclined to be more or less play or looseness, with the result that rods become badly worn and finally break under the rapid vibration of the frame and the tension of the heddles. By contrast, the present form of latch clamps a single bar so positively and securely, that relative movement between the latch and bar is prevented, with resulting prevention of wear and consequent breaking of the bar. On the other hand, if the nut which serves to normally secure the latch parts in positive, fixed and locked relation should accidentally become loosened, the spring which is then interposed between the nut and adjacent latch part operates as an auxiliary safeguard, to prevent the latch from opening and releasing the bar as would otherwise be possible, with probably disastrous results to the fabric being produced by the loom.

Another object, briefly stated, is to provide in the present invention a combined simplification of an improvement over certain earlier structures in the particular art involved, making use of details which have proved of distinct value, and adding to them the cooperation of additional details which are novel and particularly characteristic of the present disclosure.

A further object is to provide in a device of this character a shank, normally secured to one of the rails of a heddle frame, and if desired being adjustable with respect to such frame rail, said shank not being provided with the flattened and proportionately broadened head which has heretofore been in such wide use, but being substantially if not unbrokenly cylindrical in cross

section, and provided with a cut-out recess upon one lateral side adapted to receive a heddle bar inserted laterally thereinto, in combination with a substantially cylindrical sleeve having a notch extending longitudinally inwardly from its normal outer end and adapted to receive the bar, as the sleeve slides upon and towards the free end of the shank, said sleeve being also provided with a seat or other suitable radially extending offset, slidably engageable within a groove which extends longitudinally in a convenient portion of the surface of said shank, to prevent axial movement of said sleeve upon said shank, the upper end of said shank (as viewed in the detailed figures of the drawing) being reduced to provide a shoulder, which cooperates with a radially inwardly extending flange or reduced portion of the sleeve to limit relative movement of the two members longitudinally in one direction, in combination with a spiral or other suitable spring to yieldingly force the sleeve towards the free end of the shank, and a nut carried by and in threaded engagement upon the upper portion of said shank, and provided in its normal lower portion (as viewed in the drawing) with a recess to receive said spring, when said nut is employed to positively maintain said sleeve in outer operative position, and said nut when spaced from said sleeve being operative thru said spring to adjustably vary the tension upon said spring, and thereby the force with which said sleeve is held against the heddle bar supported thereby.

Herein when reference is made to the outward or inward movement of the sleeve, adjustable nut, and any other parts of the device, it is to be understood that such reference is made in lieu of such terms as "upper" and "lower" which latter strictly speaking apply only to the position of the latch as shown in Figs. 2 to 6, since in each loom harness similar latches are positioned opposite thereto in inverted position.

With the foregoing objects in mind, the invention comprises further details of construction and operation, which are brought out in the following description, when read in conjunction with the accompanying drawing, in which

Fig. 1 is an elevational view of a heddle frame in which are employed a pair of supporting latches comprising one embodiment of the invention, the upper of said latches being in depending position, while the other latch of the pair is in inverted or upright position;

Fig. 2 is an enlarged section on the line 2—2 of Fig. 1;

Fig. 3 is a horizontal section on the line 3—3 of Fig. 2;

Fig. 4 is a view similar to Fig. 2 except for the omission of the frame rail and with the locking nut in retracted position, to permit the lifting of the bar-retaining sleeve;

Fig. 5 is a view similar to Fig. 4 but showing the sleeve in retracted position, to permit the removal of the heddle bar; and

Fig. 6 is an enlarged fragmentary view, showing the spring and a portion of the shank in elevation, and adjacent portions of the nut and sleeve in section.

Referring to the drawing, a heddle frame is here shown as comprising parallel, oppositely positioned top and bottom rails 1 and 2, connected at their ends by any suitable means such as straps 3. Single heddle bars 4 and 5 extend longitudinally of the frame parallel with and slightly spaced from their respectively adjacent rails 1 and 2, and operatively support corresponding series of heddles 6, only portions of which series are shown. In describing the present invention, reference will be made only to the upper rail 1 and the latch or latches supported thereby, as the lower rail and latches are but duplicates of the former.

The rail 1 is provided with a bore 7 into which extends the reduced end portion 8 of a latch shank 9, said reduced end portion either terminating within and being in adjustable threaded engagement with the walls of said bore, or extending completely thru said bore and in such case being held in longitudinally adjusted position, in any well known manner. In the case of the latter construction it has been customary to operatively secure the shank in desired position by means of suitable nuts upon said shank, in binding engagement with the opposite surfaces of the intervening rail. This construction is mentioned merely to show that the exact manner of support and adjustably positioning of the latch shank is no part of the present invention.

In that embodiment of the invention here shown, the intermediate portion of the shank is threaded as shown at 10, while the free end portion of said shank comprises a radially enlarged head 11 of substantially cylindrical cross section, separated from the said intermediate threaded portion by a circumferential shoulder 12, said head being also provided with a cut-out recess 13, into which the heddle supporting bar 4 may be inserted laterally, so that the axis of the bar may intersect the axis of said head, as indicated in the drawing, said bar then being positively prevented from any substantial vertical movement by the opposed walls 14 and 15 of said recess.

A sleeve 16, of internal cross section corresponding to the external cross section of said head, is slidably mounted with respect to the latter and provided at its upper end with a radially inwardly extending flange 17, which cooperates with the shoulder 12 to limit the movement of said sleeve upon said head in one direction, but permits a sufficient degree of movement to allow the innermost walls 18 of slots 19, extending inwardly from the outer free end of said sleeve, to engage in binding relation the adjacent edge portion of the heddle bar 4. Said slot is centrally positioned transversely of the outer end of said sleeve, and provides a retaining tongue or the like 20 to normally overhang and operatively secure said bar within the recess 13.

A coil spring 21 preferably surrounds the intermediate portion 9 of the shank and at one end

bears against the flanged end 17 of the sleeve 16, while its opposite end bears against the innermost relatively planar surface 22 of a hollow cylindrical nut 23, which at 24 is adjustably secured to the threaded portion 10 of said shank. In the position of said nut shown in Figs. 4 and 6, the pressure of the spring 21 being relatively light permits the sleeve 16 to be raised into the position shown in Fig. 5, to permit the lateral transverse removal of the bar 4 lateral of the recess 19. On the other hand, when the nut 23 is screwed down into an intermediate position, much greater tension is placed upon said spring and consequently upon said sleeve, while screwing the nut 23 into its lowermost position as shown in Fig. 2, serves to positively lock said sleeve against upward movement, and binding the same into fixed operative position, whereby the bar 4 is rigidly gripped and held against either transverse, vertical or even longitudinal movement with respect to said latch.

In order to prevent said sleeve from rotating or in fact moving even slightly angularly about the axis of said latch head 11, and thereby shifting the slots 19 out of angular alignment with the recess 13, said head is provided at any suitable point with a longitudinally extending groove 25 into which projects the inner end of a teat 26 with which said sleeve is provided, as shown in detail in Fig. 3.

In the operation of this device the parts are assembled as shown in the drawing, but initially with the nut 23 in raised position, as shown in Figs. 4 and 6. The sleeve may then be raised into the position shown in Fig. 5, to permit the insertion of the bar 4 in the slot 13, after which the spring automatically forces the sleeve into its lower operative position, where it is held by said spring to a degree depending upon the force applied to the spring by means of and in accordance with the position of the nut upon the threaded portion of said shank. Said cap is then screwed down into its operative lowermost position, as shown in Fig. 2, in order to maintain said sleeve rigidly in operative position, as hereinbefore described. In order to remove the bar from the recess 13, the reverse operation is performed, thereby upon raising said nut permitting said sleeve to be moved against the tension of said spring in the upper position as shown in Fig. 5, whereupon the bar may be removed laterally at will.

Having thus described my invention what I claim as new and desire to secure by Letters Patent is:—

1. A latch for heddle frames, comprising a cylindrical shank, an enlarged cylindrical head providing an annular shoulder and provided with a recess, and a cylindrical sleeve slidable upon said head and comprising a tongue adapted to engage and retain a heddle bar in said recess, said sleeve being also provided with an annular flange surrounding said shank and engageable with said shoulder to limit the movement of said sleeve in one direction.

2. A latch for heddle frames, comprising a cylindrical shank, an enlarged cylindrical head providing an annular shoulder and provided with a recess, a cylindrical sleeve slidable upon said head and comprising a tongue adapted to engage and retain a heddle bar in said recess, said sleeve being also provided with an annular flange surrounding said shank and engageable with said shoulder to limit the movement of said sleeve in one direction, a spring normally forcing said

sleeve towards the free end of said head, and a nut in threaded engagement with said shank, operative to vary the tension upon said spring and in one position being directly engageable with 5 said sleeve, to lock said sleeve against the release of a heddle bar in said recess.

3. A latch for heddle frames, comprising a cylindrical shank, an enlarged cylindrical head providing an annular shoulder and provided with 10 a recess, and a cylindrical sleeve slideable upon said head and comprising a tongue adapted to engage and retain a heddle bar in said recess, said sleeve being also provided with an annular flange surrounding said shank and engageable with said shoulder to limit the movement of said sleeve in 15 one direction, said sleeve being splined upon and to prevent its rotation with respect to said latch.

4. A latch for heddle frames, comprising a cylindrical shank, an enlarged cylindrical head

providing an annular shoulder and provided with a recess, a cylindrical sleeve slideable upon said head and comprising a tongue adapted to engage and retain a heddle bar in said recess, said sleeve being also provided with an annular flange surrounding said shank and engageable with said shoulder to limit the movement of said sleeve in one direction, said sleeve being splined upon and to prevent its rotation with respect to said latch, 10 a spring surrounding said shank and engaging said flange, to normally force said sleeve towards the free end of said head, and a nut in threaded engagement with said shank, operative to vary the tension upon said spring and in one position being directly engageable with said flange, to lock 15 said sleeve against the release of a heddle bar in said recess. 5

JOHN WALKER, JR.
